UNITED STATES PATENT OFFICE.

STERLING HAIGHT BUNNELL, OF NEW YORK, N. Y., ASSIGNOR TO THE GRISCOM-SPENCER COMPANY, OF NEW YORK, N. Y., A CORPORATION OF NEW JERSEY.

DESIGN FOR ICE-CREAM-FREEZER CASING.

40,381.

Specification for Design. Patented Nov. 30, 1909.

Application filed March 29, 1909. Serial No. 486,827. Term of patent 7 years.

To all whom it may concern:

Be it known that I, STERLING HAIGHT BUNNELL, a citizen of the United States, residing in the city, county, and State of New York, have invented a new, original, and ornamental Design for Ice-Cream-Freezer Casings, of which the following is a specification, reference being had to the accompanying drawing, forming part hereof.

The figure is a perspective view of an ice cream freezer casing showing my design.

I claim—

The ornamental design for an ice cream freezer casing, as shown.

STERLING HAIGHT BUNNELL.
